COMBINED OIL CRACKING AND VISCOSITY
BREAKING PROCESSHoward V. Smith, Eldorado, Kans., assignor to
Skelly Oil Company, Tulsa, Okla.

Application September 11, 1936, Serial No. 100,366

9 Claims. (Cl. 196—49)

My invention consists in new and useful improvements in a combined oil cracking and viscosity breaking process in the nature of the so-called stage or step cracking operations.

5 For some years now, one of the trends in the oil cracking industry has been generally along the lines of this stage or step cracking, which means that the lighter elements of the charging stock which do not so readily form carbon, are subjected to drastic cracking conditions to convert them into gasoline, while the heavier elements of the charging stock which more readily form carbon are subjected to a mild cracking action which is instrumental in converting a 10 large part of them into lighter cracking stock. This lighter cracking stock may then be subjected to the drastic cracking conditions without danger of carbon formation.

20 The mild cracking of a heavy stock is known in the industry as a viscosity breaking operation as it was originally employed to reduce the viscosity of heavy asphaltic crude oil residues so as to convert them into marketable fuel oil. However, the purpose of the present day viscosity breaking is to convert as much as possible of the high boiling material into charging stock with a lower gas oil boiling range in order to produce cracking stock which may be subjected to a gasoline producing operation, or high temperature conditions, without excessive coke formation.

25 A large amount of heat is required to bring the charging stock for a viscosity breaker up to the viscosity breaking temperature, and this heat must be acquired at a high temperature level. 30 On the other hand, the hot cracked products from a high temperature cracking coil contain a large amount of waste heat at a high temperature level, which heat is difficult to recover by indirect heat exchange.

35 It is therefore an object of my invention to mix the viscosity breaker charging stock with the hot stream from the high temperature cracking coil to accomplish an economical heat exchange and more efficient utilization of waste heat. This 40 mixture may then be readily supplied with the small amount of additional heat required and, given the necessary time factor, will accomplish the desired amount of viscosity breaking.

45 It is a further object of my invention, after mixing the viscosity breaker charge with the hot stream from the cracking coil, to conduct the combined stream to a vapor separating device operated under high pressure, where residual vapors are separated from the charging stock for the viscosity breaking coil, thus relieving the

viscosity breaking coil of an unnecessary burden and increasing its capacity.

Furthermore, by thus operating the vapor separating device under a pressure equal to or greater than the pressure in the viscosity breaking coil, I eliminate the necessity of employing a pump to force the mixture through said coil. 5

Finally, it is the object of my invention to provide a process of this character which will operate to produce greater yields of gasoline from a given quantity of charging stock, with an increased capacity on the cracking still, and one which is effective for obtaining a gasoline of high octane number.

With the above and other objects in view which will appear as the description proceeds, my invention resides in the novel features herein set forth, illustrated in the accompanying drawing and more particularly pointed out in the appended claims.

20 Referring to the drawing,

Fig. 1 shows diagrammatically an operation carried out under the teaching of my invention.

Fig. 2 is an enlarged sectional view of the high pressure vapor separator, and

Fig. 3 is a top plan view of the same.

25 In the drawing, 1 represents a charging pump in feed line 2, the latter leading to a preheating coil 3 located in a conventional bubble tower 4. The discharge end of the preheating coil 3 leads into line 5 which terminates in communication with a vapor separator 6 provided with a series of suitable baffles 7 and fractionating trays 8 in its upper portion. A false bottom 9 is preferably provided in the lower portion of the vapor separator 6 dividing the same into two separate zones 10 and 11. The lower extremity of the upper zone 10 is in communication with a high pressure vapor separator 12 through line 13, having interposed therein a hot oil pump 14, the upper portion of the high pressure separator 12 discharging back into zone 10 of separator 6 through line 15. This line 15 is provided with a control valve 16 which is actuated by a liquid level controller 17 operatively attached to the 30 separator 12.

35 The details of structure of the high pressure separator 12 will best be seen from Figs. 2 and 3 where 18 represents a cylindrical vessel which may be approximately from two to four feet in 35 diameter, with relatively thick walls and having a tangential inlet 19 near its upper extremity. The lower portion of the vessel 18 tapers into an outlet 20 at the bottom, and the top of the vessel is closed by a head 21 suitably secured to radial 40

flanges 22, 23 represents a centrally disposed vapor pipe open at its lower extremity, which is disposed midway of the vessel 18, the upper end of said vapor pipe being in communication with a vapor discharge pipe 24 extending through the head 21. Suitable flanges are provided on the tangential inlet 19, the liquid outlet 20 and vapor outlet 24 to facilitate the connection of these points into the system.

10 Returning now to Fig. 1, a line 25 leads from the outlet 20 of high pressure vapor separator 12 to the inlet of a viscosity breaking coil 26 located in furnace 27, the discharge end of said coil being connected by line 28 to the lower portion of zone 11 of the first mentioned vapor separator 6, a throttle valve 29 being located in line 28.

15 A line 30 leads from the bottom of zone 11 to a small vessel 31, the latter discharging through line 32 and cooling coil 33 to a suitable storage 20 point not shown. The upper portion of zone 11 is in communication with the lower portion of zone 10 by means of line 34.

25 A line 35 leads from the top of vapor separator 6 through a heat exchanger 36 and into the lower portion of the bubble tower 4, the top of which discharges through line 37 and condenser 38 into a gas separator 39 having a gas discharge line 40 at its upper end, and a liquid discharge line 41 at its lower end. The lower portion of the gas separator 39 is connected by line 42 back into the upper portion of bubble tower 4, a suitable pump 43 being provided in the line 42. A line 44 and cooling coil 45 may lead from an intermediate point in the bubble tower.

30 The bottom of the bubble tower 4 is provided with a discharge line 46 which branches off into line 47 provided with pump 48, said line 47 passing through the heat exchanger 36 to the inlet end of high temperature cracking coils 48 in the furnace 27. Through line 49, the discharge end 40 of cracking coils 48 by-passes the viscosity breaker 26 and communicates with the inlet end of a top bank of coils 50, the latter being in communication with a series of roof tubes 51 and floor tubes 52. From the floor tubes 52 a line 45 53 leads to a final bank of coils 54 interposed between the viscosity breaking coils 26 and the top bank of coils 50, said coils 54 discharging through line 55 into line 13 leading to the high pressure vapor separator 12.

50 Another branch line 56 leads from line 46 from the bubble tower 4 to line 28 entering the lower zone 11 of vapor separator 6, a suitable pump 57 being provided therein.

55 The lower portion of the bubble tower 4 may be in communication with a vessel 58 by means of line 59, said vessel discharging at its bottom through line 60 and pump 61 into the upper portion of the vapor separator 6, suitable jets 62 being provided in the top of said vapor separator.

60 A line 63 leads from a low point in the vapor side of heat exchanger 36 to the vessel 58.

Having thus described an example of a set-up by means of which my improved process may be carried out, its operation is as follows:—

65 The fresh charge, which may be gas oil, topped crude or any desired type of cracking stock, is pumped into the system by pump 1 through line 2, entering the preheater or heat exchange coil 3 in the bubble tower 4. In this preheater, the charge is raised to a temperature of approximately between 500° F. and 550° F. and it then passes through line 5 into the upper zone 10 of vapor separator 6 where it commingles with the hot vapors from the cracking still, the baffle plates 7 facili-

tating the commingling of these products. The liquid collected in zone 10 above the false bottom 9 is discharged through line 13 and forced by the hot oil pump 14 into the upper portion of the high pressure vapor separator 12.

5 Due to the tangential inlet 19 into which line 13 discharges, a centrifugal motion is set up in the separator 12 and the vapors separated therein pass out through line 15 and control valve 16 back into zone 10 at a point above the discharge line 13. The control valve 16, as before stated, is actuated by a liquid level controller 17 attached to the high pressure vapor separator 12, thereby automatically regulating the return of vapors from the high pressure separator 12 to the first separator 6. I have found that appropriate temperatures for the material in the high pressure vapor separator 12 are from 825° F. to 900° F., but even higher temperatures may be used on occasions. A suitable pressure range for this vapor separator is from 100 to 800 pounds.

10 From the bottom of the vapor separator 12, the separated liquid enters line 25 and passes through the viscosity breaking coil 26 in furnace 27 where it is heated to temperatures of from 850° F. to 950° F. The oil passes from the viscosity breaking coil through line 28 and throttle valve 29 into the lower zone 11 of vapor separator 6 in which the fuel oil is separated from the vapors and passes out into the small vessel 31, and from thence through line 32 and cooling coil 33 to storage. The liquid level in the vessel 31 is kept sufficiently low that no level of liquid accumulates in the zone 11, and in this way the tar or fuel oil remains in the vapor separating zone for a 35 very short time. If necessary, the temperature in the zone 11 may be reduced by circulating some gas oil from the bottom of the bubble tower 4 through the line 46, the pump 57 and the line 56.

40 The vapors from this zone 11 pass out through line 34 into the lower portion of zone 10 where they commingle with the vapors from the high pressure vapor separator 12 and the fresh charge oil.

45 The commingled vapors in the zone 10 of the vapor separator 6 pass upwardly, contacting the baffles 7, through fractionating trays 8 which are cooled by a stream of reflux sprayed in through nozzles 62, and the fractionated vapors pass out through line 35 and heat exchanger 36 into the 50 lower portion of the bubble tower 4 where said vapors are fractionated in the conventional manner. By reason of the fractionation which takes place in the zone 10 of vapor separator 6, the heavier constituents of the vapors are condensed 55 and fall back to pass through the viscosity breaking system, and the gas oil condensate which collects in the bottom of the bubble tower 4 is a clean cracking stock which may be subjected to very high cracking temperatures without excessive carbon formation.

55 Condensate which forms in the heat exchanger 36 from the vapors, passes out through the line 63 into the vessel 58, where it mixes with gas oil from bubble tower 4 entering through line 59, and passes out through line 60 and pump 61 through the sprays 62 into the top of the vapor separator 6.

70 Cracked gasoline and gas pass out from the top of the bubble tower 4 through line 37 to condenser 38, and from thence to gas separator 39. There the uncondensable gases are discharged through line 40 and the gasoline through line 41 to suitable storage. A quantity of gasoline may be returned by line 42 and pump 43 to the top 75

5 of the bubble tower 4 for controlling the fractionation. A side stream to be used for furnace oil or for other purposes may be withdrawn from the bubble tower 4 through the line 44 and cooling coil 45, if desired.

10 The gas oil condensate collects in the bottom of the bubble tower 4 and is discharged through line 46 and forced by pump 48 through branch line 47, through heat exchanger 36 into the lower bank of cracking coils 48 in furnace 27, and from thence through line 49 into the top bank of coils 50, through the roof tubes 51, the floor tubes 52, and finally through the intermediate bank of cracking coils 54, from whence it is discharged 15 into line 43 leading to the high pressure vapor separator 12. During its passage through the high temperature cracking coils, the oil is preferably heated to a temperature of from 925° F. to over 1000° F.

20 It will be apparent that in the operation of separator 12, sufficient oil should be maintained in the lower part of the separator to actuate the float which in turn controls the valve 16 for releasing the vapors into the fractionating system, 25 and that in a small separator of this type, there is insufficient space to afford the necessary time factor for accomplishing cracking of either vapor or liquid. Therefore, any further cracking of the mixture of hot cracked products and reflux 30 condensate entering the high pressure separator 12 is minimized during the separation step.

35 It will thus be seen that with my improved combined cracking and viscosity breaking process, with the high pressure vapor separating step interposed between the point of mixing of the cracked stream with the heavy oil stream, and the viscosity breaker, a large part of the light products produced in the vapor phase operation are removed from the stream and do not pass 40 through the viscosity breaking coil, which relieves a needless burden on the system and affords a far greater capacity for viscosity breaking in a coil of a given size.

45 Furthermore, it will be apparent that the greater yields of gasoline produced by my process are obtained by the viscosity breaking operation which converts a maximum proportion of the charging stock into clean cracking stock, and a minimum proportion into tar. In this particular type of viscosity breaking operation, a maximum of viscosity breaking may be readily obtained because the high temperature at which the charge enters the viscosity breaking coil makes necessary the addition of only a small 50 amount of heat through the walls of the tubes, a condition which minimizes any coking tendency in the tubes.

55 The increased capacity obtainable by my process is the result of the efficient utilization of the heat in the cracking stream as hereinbefore described, and the operation of the cracking coil on a clean gas oil stock which permits high rates of heat input into the tubes without danger of carbon formation.

60 As before stated, my process is effective for obtaining a gasoline of high octane number, and it is to be noted that this is the result primarily of high cracking temperatures to which the clean gas oil stock can be subjected. The viscosity 65 breaking operation produces a small amount of gasoline but it has been found that when the viscosity breaking operation is conducted at temperatures near 900° F. or higher, this gasoline has a very satisfactory octane number.

70 75 From the foregoing it is believed that the ad-

vantages and operation of my process may be readily understood by those skilled in the art without further description, it being borne in mind that numerous changes may be made in the details disclosed without departing from the spirit 5 of my invention as set out in the following claims.

What I claim and desire to secure by Letters Patent is:—

1. The method of treating hydrocarbon oil 10 comprising cracking a clean oil distillate, discharging the cracked distillate into a high pressure separating zone admixed with reflux condensate from a refluxing zone maintained at a lower pressure than said separating zone, to rapidly 15 separate vapors from liquids while minimizing further cracking, subjecting the separated hot vapors to reflux condensation with an incoming stream of heavier charging oil in said refluxing zone, to form said reflux condensate, 20 subjecting the liquid from said separating zone to a mild cracking, further separating the products of said mild cracking, removing tar from the system, fractionating the vapors from said refluxing zone and said further separation, and condensing and collecting the fractionated vapors.

2. The method of treating hydrocarbon oil comprising cracking a clean oil distillate, discharging the cracked distillate into a high pressure separating zone admixed with a stream of 30 reflux condensate from a refluxing zone maintained at a lower pressure than said separating zone, to rapidly separate vapors from liquids without substantial further cracking, subjecting the separated hot vapors to reflux condensation 35 with an incoming stream of heavier charging oil in said refluxing zone, to form said reflux condensate, fractionating the vapors from said refluxing zone, subjecting the liquid from said separating zone to a mild cracking, further separating 40 the products of said mild cracking, removing tar from the system, subjecting the vapors from said further separation to refluxing action in said refluxing zone and condensing and collecting the vapors from said fractionating zone as the desired product.

3. The method of treating hydrocarbon oil comprising cracking a clean oil distillate, discharging the cracked distillate into a high pressure separating zone admixed with reflux condensate 50 from a refluxing zone maintained at a lower pressure than said separating zone, to rapidly separate vapors from liquids without substantial further cracking, subjecting the separated hot vapors to reflux condensation with an incoming 55 stream of heavier charging oil in said refluxing zone, to form said reflux condensate, subjecting the liquid from said separating zone to a mild cracking, further separating the products of said 60 mild cracking, removing tar from the system, jointly fractionating the vapors from said refluxing zone and said further separation to form said clean oil distillate, and condensing and collecting said fractionated vapors.

4. A process of treating heavy hydrocarbon oils 65 to produce lighter hydrocarbons and gasoline, which includes preheating a stream of said heavy hydrocarbons, separating vapors from liquids in a primary separating zone, conducting the separated liquid to a second separating zone maintained at a pressure higher than said primary separating zone, admixed with a stream of hot cracked products from a severe cracking zone, rapidly separating vapors from liquids in said second separating zone without substantial further 70 75

- cracking, cracking the liquids from said second separating zone in a less severe cracking zone, separating the vapors and liquids resulting from said less severe cracking, removing tar from the system, and subjecting the vapors from all said separating zones to reflux condensation in a common refluxing zone.
5. A process of treating heavy hydrocarbon oils to produce lighter hydrocarbons and gasoline, 10 which includes preheating a stream of said heavy hydrocarbons, separating vapors from liquids in a primary separating zone, conducting the separated liquid to a second separating zone maintained at a pressure higher than said primary separating zone, admixed with a stream of hot cracked products from a severe cracking zone, rapidly separating vapors from liquids in said second separating zone without substantial further cracking, cracking the liquid from said second 15 separating zone in a less severe cracking zone, separating the vapors and liquids resulting from said less severe cracking, removing tar from the system, subjecting the vapors from all said separating zones to reflux condensation in a common refluxing zone, subjecting the resulting vapors to fractionation to separate a clean stock, and cracking said clean stock in said severe cracking zone to produce said hot cracked products.
- 20 6. The method of treating hydrocarbon oil comprising cracking a clean oil distillate under a temperature of at least 925° F., discharging the cracked distillate into a high pressure separating zone admixed with reflux condensate from a refluxing zone maintained at a lower pressure than said separating zone, to rapidly separate vapors from liquids while minimizing further cracking, subjecting the separated hot vapors to reflux condensation with an incoming stream of heavier 25 charging oil in said refluxing zone, to form said reflux condensate, subjecting the liquid from said separating zone to a mild cracking at a temperature of from 850° F. to 950° F., further separating the products of said mild cracking, and removing tar from the system, jointly fractionating the vapors from said refluxing zone and said further separation, and condensing and collecting the fractionated vapors.

7. The method as claimed in claim 6 wherein the pressure maintained in said high pressure separating zone is from 100 pounds to 800 pounds per square inch.

8. The method of treating hydrocarbon oil 5 comprising cracking a clean oil distillate at a temperature of at least 925° F., discharging the cracked distillate into a high pressure separating zone maintained at a pressure of from 100 pounds to 800 pounds per square inch admixed with reflux condensate from a refluxing zone maintained at a lower pressure than said separating zone, to rapidly separate vapors from liquids while minimizing further cracking, subjecting the separated hot vapors to reflux condensation with an incoming stream of heavier charging oil in said refluxing zone, to form said reflux condensate, said incoming stream having been preheated to a temperature below cracking, subjecting the liquid from said separating zone to a mild cracking 20 at a temperature of from 850° F. to 950° F., further separating the products of said mild cracking, and removing tar from the system, fractionating the vapors from said refluxing zone and said further separation, and condensing and collecting 25 the fractionated vapors.

9. The method of treating hydrocarbon oil comprising cracking a clean oil distillate, discharging the cracked distillate into a high pressure separating zone admixed with reflux condensate from a refluxing zone maintained at a lower pressure than said separating zone, to rapidly separate by centrifugal action vapors from liquids while minimizing further cracking, subjecting the separated hot vapors to reflux condensation with an incoming stream of heavier charging oil in said refluxing zone, to form said reflux condensate, subjecting the liquid from said separating zone to a mild cracking, further separating the products of said mild cracking, and removing tar from the system, commingling and then fractionating the vapors from said refluxing zone and said further separation, and condensing and collecting the fractionated vapors.

45 HOWARD V. SMITH.
